ABSTRACT OF THE DISCLOSURE

In decorating ceramic elements, such as wall and floor tiles, a solvent is sprayed on a raw-glazed tile as it travels on a conveyor member. Next a pattern of ceramic dyes printed on a carrier element, and with a lacquer coat on the surface opposite the carrier element, is placed on the tile with the lacquer coat in contact with the tile. The solvent previously applied to the tile dissolves the lacquer coating. Then, in turn, the pattern is pressed against the tile and the carrier element is removed before the tile is baked.

SUMMARY OF THE INVENTION

The invention concerns a method for machine-decorating ceramic wall and floor tiles and a device for carrying out the method.

It is known to decorate wall and floor tiles automatically by screen printing. In this direct printing technique, it is only possible to utilize relatively coarse drawings, due to printing difficulties and the resulting register differences. In a multicolor print, the register differences become so considerable that the decoration loses its appeal. Since screen printing presses can only print the plane surface of the tile and the tile has a significant curved surface over 1-3 mm. at its edge zones, it is not possible with this technique to apply the decoration over the entire surface of the tile. In laying such decorated tiles gaps result which make a continuous picture or pattern quite unattractive.

It is also known to decorate tiles manually by applying decals or the like which embody the pattern or design to be placed on the ceramic article. Depending on the choice of colors, the tiles are baked at 720° C. (glaze-on decoration) or at about 1050° C. (glaze-on decoration for intensive fire). The decorations obtained in this manner are more or less resistant to abrasion and chemical influences. Contrary to screen printing decoration, this decorating technique avoids the disadvantages of leaving the edges undecorated, since the decals can be made large enough so as to allow decorating of the curved edges as well. The main disadvantage of this decorating technique, however, is that each decal or pattern has to be placed individually by hand and that, moreover, the excess water transferred in the process has to be removed by a rubber or plastic squeegee-like member for preventing baking defects. Such manipulations are expensive and time-consuming and, therefore, limit the application of this decorating technique to very expensive high style decorations.

Accordingly, for a long time the tile industry has been looking for a mass production method of automatically applying attractive decoration to tiles. Such a method has to combine the advantages of automatic screen printing decoration and the advantages of manual decal decoration. The use of the known decals or patterns for machine decorating so far has failed due to the fact that these patterns, after removal from the carrier paper, can not be manipulated by machine, since they then lack the necessary stability. One the other hand, if these patterns are applied together with their carrier paper onto the tile,

2

the pattern comes off the tile again or is at least displaced when one tries subsequently to remove the carrier paper from the pattern. All attempts in this direction have shown again and again that patterns or decals are not suitable for the automatic decorating of ceramic articles generally and for wall or floor tiles in particular, and it is always necessary to revert to the manual decorating techniques.

The present invention has as its object to disclose a process for machine decorating ceramic wall and floor tiles with patterns of ceramic dyes.

Therefore, in accordance with the present invention, ceramic articles are decorated by utilizing decal-like members containing a design or a pattern of ceramic dyes printed on a carrier element which is provided with a water-soluble and/or meltable separating layer and bonded by at least one lacquer coating. Initially, the raw-glazed tile is sprayed with a solvent for dissolving the lacquer coating, the pattern is then placed on the sprayed surface and the gloss and decoration baking is effected in one working step. It is the particular merit of the invention to have recognized for the first time that with this special pattern, which, on the one hand, is printed onto an easily removable carrier and, on the other hand, is bonded by a lacquer mask, a decorating process is available which is suitable for automatic machine decoration of wall and floor tiles. This suitability is based on the fact that the adherence between pattern and tile, on the one hand, and between pattern and carrier paper or element, on the other hand, is basically different. Whereas the bonding between pattern and carrier paper is effected by a water-soluble and/or meltable separation layer, such as, a polyglycol layer, the bonding between the pattern and the tile is effected by the application and subsequent penetration of the lacquer mask and/or the ceramic dyes into the raw-glazed tile. The latter bonding is so intensive that when the carrier paper is detached and subsequently removed from the pattern applied to the tile, there is no danger of removing the pattern with it or even displacing it. This is one of the basic reasons for the suitability of the inventive procedure for machine-decoration of tiles.

A further decisive advantage is to be seen in the fact that due to the different adherences the pattern can remain connected with the carrier paper during the application to the tile and the pattern therefore retains the stability which is necessary for machine manipulation.

Another advantage is the non-hygroscopic nature of the lacquer mask. If water is used for dissolving the separating layer between the pattern and carrier paper, the lacquer mask protects the underlying water-sensitive raw glaze. If, in a further development of the invention, the carrier of the pattern is a polyglycol-coated paper which is removed from the pattern by water, the lacquer coating and the polyglycol layer dissolved in water repel each other due to their contrasting non-hygroscopic and hygroscopic nature, which facilitates the removal of the carrier paper in an advantageous manner.

As a suitable embodiment of the invention, it is suggested that the raw-glazed tile is subjected to the following consecutive steps:

Spraying the raw-glazed tile with a solvent for dissolving the lacquer coating, applying the pattern so that its lacquer coating contacts the tile, pressing the pattern on the tile, and dissolving and removing the carrier member from the pattern. In carrying out this process the tile is placed on a conveying device and passes, in sequence, a spraying device for the solvent, a dispensing device coating with a supply container for the patterns which applies one pattern to each tile, at least one pressure roller which presses the pattern onto the tile, and a device for dissolving and removing the carrier from the pattern.

In cases where it is not suitable to work with water as the solvent for the separating layer between pattern and carrier, it is suggested, according to the invention, that the carrier of the decal or pattern be a wax-coated heat conducting foil which is removed from the pattern by the influence of heat.

In a further embodiment of the invention, it is suggested that the lacquer coat be slightly larger than the tile to be decorated. This offers very good protection against water influences for the raw glaze layer of the tile under the lacquer layer. Moreover, it may be very suitable to make the pattern slightly larger than the tile so that at least one of the four edges of the tile can also be decorated. These tiles with decorated edges are needed as border tiles.

The various features of novelty which characterize the invention are pointed out with particularity in the claims annexed to and forming a part of this disclosure. For a better understanding of the invention, its operating advantages and specific objects attained by its use, reference should be had to the accompanying drawings and descriptive matter in which there is illustrated and described a preferred embodiment of the invention.

BRIEF DESCRIPTION OF THE DRAWING

The drawing is a schematic illustration of one embodiment for carrying out the invention.

DETAILED DESCRIPTION OF THE INVENTION

As shown in the drawing, an elongated conveyor belt 1 moves raw-glazed ceramic tiles 2 in the direction indicated by the arrow. The tiles 2 are secured in position on the conveyor belt 1 and are carried first, past a spray device 3 which contains ethylglycolacetate as a solvent. Next the tiles move under a storage container 4 for patterns 5 of ceramic dyes from which a device 6 dispenses the patterns 5. In turn the tiles 2 travel under pressure rollers 7 to 10 by which the patterns are pressed onto the tiles 2. After leaving the rollers the tiles 2 are sprayed by a second spraying device 11 containing heated water. Finally the tiles move under a further pressure roller 12 and a sponge member 13. Below the spraying device 3 a collecting container 14 is provided which collects the excess solvent and recycles it to the spraying device for further use. In addition, a collecting container 15 for the excess water is arranged below the spray means 11, the pressure roller 12 and the sponge member 13.

In the storage container 4, the patterns 5 are stacked so that the lacquer coat bonding the pattern is directed downwardly and, accordingly, the polyglycol-coated paper acting as a carrier is directed upwardly. The dispensing device 6 includes a rubber roller whose rotation drive is coupled with the drive of the conveyor belt, not shown. When rotating, the rubber roller 6 pushes the lowermost pattern 5 from the storage container 4 in the direction of travel of the conveyor belt 1 between a pair of rollers 16, which direct the pattern 5 over a roller 17 to an abutment 18 where the tile 2 to be decorated abuts. As soon as the tile 2 and the pattern 5 are in register with one another, the abutment 18 is removed and the tile with the pattern is conducted along the conveyor belt 1. The pressure roller 7 then presses the pattern 5 onto the tile 2 so that the solvent, ethylglycol-acetate, on the raw-glaze is applied to the lacquer coat and the ceramic dyes of the pattern. This application procedure is continued during the passage of tile with its pattern under the additional pressure rollers 8, 9 and 10. The lacquer coat or layer and the ceramic dyes thus penetrate into the raw-glazed tile establishing an intimate bond between the pattern and tile.

Subsequently, as the tile 2 with the pattern 5 moves under the second spray device 11 it is sprayed with heated water on the polyglycol-coated carrier paper facing upwardly. Due to the absorbency of the carrier

paper, the heated water penetrates the polyglycol layer and softens this layer within seconds.

The tile 2 is thereupon moved past the further pressure roller 12 which removes the excess water on the carrier paper. The carrier paper is then removed by the sponge member 13. This sponge member has the shape of a rotation roller whose tangential direction of movement forms a right angle with the direction of movement of the tile 2 and/or the conveyer belt 1. It is also possible, however, that the two directions of movement form any other angle. The right angle is the most suitable because the removed carrier paper in that case cannot fall back on the conveyer belt 1. After the sponge member, the decorated tiles 2 then reach storage chambers where they are stored until the baking step.

If, instead of the polyglycol coated paper as carrier for the ceramic pattern, a wax coated, heat conductive foil is used, the spraying means 11, pressure roller 12 and the sponge band 13 are replaced by a heat source whose radiation is directed on the foil and a blower which directs the foil away from the pattern. In this case it is particularly suitable to combine the heat source and blower in a single device, such as, in a hot air producing drier unit.

Instead of the elongated conveyer belt 1, it is of course possible to provide a revolving conveyer for the tiles 2.

If the pattern 5 is slightly larger than the tile 2 so that at least one of the four edges can also be decorated, at least one of the pressure rollers 7 to 10 has to be designed such that it contacts the edges of the tile.

It is the possibility of edge decoration of the tiles which brings particular advantages to the inventive procedure as compared to screen printing decoration. By using the specially printed ceramic pattern it is moreover possible to do pre-sorting in the printing location, which makes the number of rejects in the decorating stage considerably smaller than in the direct printing procedure. Since no restrictions have to be made for ceramic multicolor printing on paper in respect to register and number of colors, it is possible to create considerably more attractive decorations than in direct printing procedures.

A further important advantage of the inventive procedure is that by the penetration of the pattern into the raw glaze a decoration can be achieved which is completely equal in resistance to abrasion and chemical influences to the much more expensive below-glaze decoration. This is of particular importance for floor tiles.

What is claimed is:

1. Method of decorating a raw-glazed ceramic tile with a pattern of ceramic dyes printed on a carrier element provided with a separating layer between the carrier element and the pattern and with a lacquer coating on the surface of the pattern opposite the separating layer for bonding the pattern, wherein the improvement comprises subjecting the raw-glazed tile in succession to the steps of positioning the raw-glazed tile on a travelling support surface with the surface of the tile to be decorated directed upwardly and conveying the tiles along a path of travel for sequentially effecting the decorating process at spaced stations along the path of travel, spraying a solvent on the surface of the raw-glazed tile to be decorated which solvent is capable of dissolving the lacquer coating on the pattern, automatically depositing and positioning the pattern on the upper surface of the tile and applying the pattern so that the lacquer coating on its surface contacts the solvent sprayed on the surface of the raw-glazed tile and with the carrier element located on the face of the pattern directed outwardly from the tile, dissolving the lacquer coating on the pattern by means of the solvent and affording the subsequent penetration of the lacquer coating and/or the ceramic dyes into the raw-glazed tile, pressing the pattern against the surface of the tile, separating the carrier element from the pattern, removing the carrier element from the pattern on the tile, and gloss and decoration baking the tile in a single operation.

2. The method, as set forth in claim 1, characterized therein that the carrier element on the pattern is a polyglycol-coated paper, and using heated water for separating the carrier element from the pattern.

3. The method, as set forth in claim 1, characterized therein that the lacquer coating is slightly larger than the surface of the tile being decorated.

4. The method, as set forth in claim 3, characterized therein that the size of the pattern is slightly larger than the surface of the tile being decorated so that at least one of the four edges of the tile can be covered by the pattern.

5. The method, as set forth in claim 1, characterized therein that the carrier element of the pattern is a wax-coated heat conducting foil, and applying heat to the carrier element separating the carrier element from the pattern.

6. The method, as set forth in claim 5, characterized therein that after separating the foil from the carrier element applying a stream of hot air over the tile for removing the carrier element from the tile.
